UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

MEANS FOR DISCHARGING MATERIALS FROM RAILROAD-CARS.

1,342,088.

Specification of Letters Patent.

Patented June 1, 1920.

Application filed December 26, 1918. Serial No. 268,316.

To all whom it may concern:

Be it known that I, ARGYLE CAMPBELL, a citizen of the United States, residing at Chicago, in the county of Cook and State of Illinois, have invented a certain new and useful Improvement in Means for Discharging Materials from Railroad-Cars, of which the following is a full, clear, concise, and exact description, reference being had to the accompanying drawings, forming a part of this specification.

My invention relates to means for discharging materials from a railroad car or other similar containers. In the specific application of my invention, described herein and illustrated in the drawings, it is embodied as a means for discharging grain from railroad cars.

In the transportation of grain by railroads, usually box cars are employed, the said cars ordinarily being provided with a door on either side. The accidental discharge of grain through the door opening is prevented by the employment of various means—as, for instance, one-piece doors, or boards sometimes employed as an integral structure, and sometimes used in a plurality of pieces, but whatever means are employed, great difficulty has heretofore been experienced in making the initial discharge of the grain, and it has been necessary to remove the grain door or the boards or other means of closure either by shoveling the grain away from the door-closing means in order to relieve the pressure thereon, or to employ bars or other tools to disengage the boards or grain doors from the door opening. Heretofore, this has resulted not only in great difficulty in procuring the initial discharge of grain and in a scattering of the grain, but it has also been necessarily destructive of grain doors or the boards, or other door-closing means. One of the objects of my invention is to overcome this difficulty by providing a simple, efficient and easily-operated means for removing the grain, particularly from those parts immediately adjacent the side doors of a railroad car.

In the drawings and the description hereinafter following, I have illustrated and described one embodiment of my invention, although it will be apparent that other embodiments are possible without departing from the spirit of this invention. Other ob-

jects of my invention will appear from the description thereof hereinafter following.

Referring to the drawings forming a part of this specification, Figure 1 illustrates a side view of a portion of a railroad box car showing a side door opening and the immediately adjacent parts of the device embodying my invention. Fig. 2 is a top plan view of a section of the car immediately back of a side door thereof. Fig. 3 is an end view of the discharging means embodying my invention, shown in its position in relation to the floor of the car. Fig. 4 is an enlarged, vertical, sectional view taken on line 4—4 of Fig. 1. Fig. 5 is a longitudinal, sectional view taken on line 5—5 of Fig. 4. Fig. 6 is a detail of one of the links shown in perspective. Fig. 7 is an enlarged detail of a locking device. Fig. 8 is a sectional view taken on line 8—8 of Fig. 3. Fig. 9 is an enlarged detail showing the operating shaft in perspective and Fig. 10 is a perspective view of a locking pawl.

Referring to the drawings, the numeral 7 indicates the side of a box car, a portion of which is shown in Fig. 1, having a side door opening 8 therein, a common form of door therefor referenced 9, a door sill 10, a lintel 11, one of the door posts being indicated at 12 and the siding referenced 13. It will be understood that the door opening in the carrying of a cargo of grain is closed by boards or a grain door, and, in the illustration shown in Fig. 1, boards are illustrated, the same being referenced 14. The floor of the car is best shown in Figs. 3, 4 and 5, being referenced 15 therein. 16 indicates a side sill of the car and 17 an opening in the floor of the car adapted to receive the upper portion of the grain discharging means hereinafter described. The grain discharging means includes a chute 18 preferably formed of a casting, although it will be apparent that other materials may be used, the said chute having a substantially vertical discharge opening at its upper end, indicated by the numeral 19, which opening, in its downward course, turns outwardly, as at 20, in its relation to the railroad car. The said chute is provided at its upper end with outwardly extended flanges, 21, which are inset in the car floor so that the upper surface thereof is in substantially the same plane as the surface of the floor, and the upper opening of said chute is provided with a door 22.

22, which, in preferable construction, is hinged at its outer end to the chute or casting by means of the pin 122 and the butts 23. The hinge is arranged underneath the 5 frame of the door opening and the said door is provided, at its other end, with the butts or lugs 25 suitably perforated for the passage of the pin 26, by means of which the said door is connected to the operating 10 mechanism generally referenced 27 and hereinafter more specifically described. The said chute 18 is provided at either side with outwardly projecting lugs 28 which are adapted to secure the chute firmly to the 15 car, the said lugs resting upon the angle irons 29-29 mounted transversely of the car, and, in the particular embodiment shown, held at their outer ends by a further angle 30 which is secured along the under- 20 face of the side sill and are held at their inner ends by the Z-bar 31, which, in the particular car shown, is a usual part of the car structure. It will be obvious that other means may be employed for upholding 25 the angle irons or members 29-29, which are designed to principally support the chute 18. The said supporting means are secured together in any suitable way—as, for instance, by the rivets 32-32. 30 Near its lower end, the chute 18 is outwardly provided with a flange 33 which engages the underface of the lower flange 34 of the side sill 16, which, in the particular illustration, is of channel form. It will be apparent that 35 other similar means may be employed to engage the chute at its lower end to the side sill or other adjacent parts of a railroad car. In the particular embodiment of my invention shown in the drawings, the chute 40 at the point indicated is riveted to the flange 34 of the side sill, as shown at the numeral 35.

At the lower end of the chute brackets 36-36 are provided, suitable bearing lugs 45 37-37 in which is mounted the shaft 38, the said shaft being provided at one end—for instance, at the end 39—with an operating handle 40, the said operating handle being provided with a shoulder 41, which 50 is adapted to be engaged by the locking pawl 42. The pawl 42 is pivoted as at 43 to the chute and is provided at its free end with a shoulder 44, having a perforation 45, which is adapted when the pawl engages 55 the shoulder 41 of the operating handle to aline with the perforation 46 therethrough for the passage of a seal 47 to lock the pawl against accidental or mischievous displacement from its engagement with the handle. 60 The shaft 38 is preferably hollow, as indicated at 48 in Fig. 8 of the drawings, and has near the handle end thereof a rounded portion 49 that is mounted within the bearing 50 formed in one of the bearing lugs 37, and, at the terminus of said

rounded portion, has a non-circular, preferably squared, portion 51, upon which is mounted the arm 52. Beyond said non-circular portion, the shaft is provided with a further circular portion 53 which is received within the bearing 54 of the other bearing lug 37 and the shaft is also provided with a projecting terminal portion 55 which extends through the opening 56 in the bracket and is there provided with a pin 57 adapted to hold the shaft within its bearings formed in the brackets 36. To permit the assembling of the arm 52 upon the shaft, the terminal portion 55 of said shaft is of smaller diameter than the adjacent portion, and each successive portion of the shaft hereinbefore described from said end to the handle end is larger than its adjacent portion, with the bearings therefor suitably conformed so that the arm 52 may be placed in its position in the slot 58 between the brackets 36 and the shaft inserted therethrough until its bearing parts are in suitable engagement in the portion of the brackets adapted to receive them, and the non-circular part is engaged within a similarly conformed non-circular opening 59 in the arm 52, thus securely locking the arm upon the said shaft and requiring the arm to turn upon the rotation of the shaft. The said arm 52 is provided with a lug 60, the edge 61 of which forms the arc of a circle struck about the axis of the shaft 38, which lug is adapted to fill the slot between the brackets 36, through which the said arm is extended into the interior of the chute, so that in any position of the arm when rotated by the shaft the said lug fills the said slot between the brackets to prevent the escape through 105 the said slot of grain passing down the chute. A link 62, bifurcated at both ends, as indicated at 63, is pivoted to the arm 52 by means of the pin 64, which is suitably secured against accidental displacement by a cotter 65. At its other end, the link 62 is pivoted to the lug 25 of the door 22 by means of the pin 26, which is secured against accidental displacement by the cotter 67. A flange 68 is provided 110 around the edges of the door 22, which is adapted to fit against the lower face of the frame 69 surrounding the chute door 22 in order to provide a tight closure of the chute door. It will be noted that the 115 opening of the chute extends downwardly from the floor of the car and then outwardly so that grain traversing the said chute may be carried outwardly away from the car and conveyed therefrom by a suitable trough or chute which may be placed to lead the discharging grain to a bin or other receptacle therefor.

Upon loading a car with grain, the chute door will be closed and locked in its closed 130

position by means of the link 62 and the arm 52 through the medium of the operating shaft, which is secured against rotation by the pawl 42, the said pawl being locked by 5 an ordinary seal to prevent interference therewith by trespassers or its accidental displacement. When it is desired to discharge a cargo of grain from the car, the seal is removed from the pawl, the handle 10 is turned in a counter-clockwise direction rotating therewith the arm 52 and opening the chute door through the medium of the link 62 until the door is swung to its open position, which will be that shown by the dotted lines in Fig. 4 of the drawings, that is, 15 depending in the chute, the then position of the link 62 and the arm 52 being likewise shown by dotted lines in Fig. 4. Thereupon the grain above and about the said chute 20 door will descend through the chute by gravity and be conveyed to its receptacle until the grain in front of and about the grain door of the car will have been discharged when the said grain door or grain-retaining 25 boards may be removed, and the further discharge of grain may be continued in the usual manner or it may be shoveled into the said chute and conveyed to the receptacle therefor. This means of discharging the 30 load about the doors of the car is simple and efficient and more fully conveys away the grain than does a device which permits of its discharge through the grain door itself, and also enables one to readily make removal 35 of the grain door or grain-retaining boards without the destruction thereof or injury thereto. Upon the completion of the unloading operation, the handle 40 is employed to return the chute door to its closed 40 position, the arm 52 being prevented from rotation beyond alinement with the link 62 by means of the stop shoulder 70 provided upon the inner surface of the chute. By reason of this alinement the weight of the 45 chute door and its load is conveyed directly to the operating shaft without danger of the accidental displacement of the arm and link from their locked position, which is further guarded against by the pawl and seal there- 50 for hereinbefore described.

From the preceding description, considered in connection with the drawings, it is evident that my improved grain discharging arrangement can be furnished to railroads

as an article of manufacture for application 55 to the ordinary box cars now in service so that the railroads can readily change over their box cars for the carrying of grain or other material in bulk at comparatively small expense and without any radical 60 changes in the construction of the box car. Substantially the only change required in the box car would be the provision of an opening to accommodate the chute with any suitable securing means for the chute. 65

It will also be noted that the construction of the chute and its door closure is very substantial and adapted to sustain heavy loads such as might occur in trucking of packaged articles into and out of the car. Ordinarily, 70 where only one chute is provided adjacent each side door of the car, the chute will be disposed centrally of the door and is preferably made of such width that the usual trucks would straddle the door. However, 75 the chute and its door are of sufficiently strong construction to stand any ordinary trucking load.

I claim:

1. In a railroad car, the combination with 80 the car floor having an opening therein, of a chute leading downwardly from said opening, a door for said chute, a shaft mounted on said chute, flexible operating means connecting the shaft and the door, the shaft being provided with an operating handle, the said handle being provided with a lug, and a pawl mounted on said chute adapted to engage said lug to secure the shaft against rotation therein. 90

2. In a railroad car, the combination with the car floor having an opening therein, of a chute leading downwardly from said opening, a door for said chute, a shaft mounted on said chute, flexible operating 95 means connecting the shaft and the door, the shaft being provided with an operating handle, the said handle being provided with a lug, and a pawl mounted on said chute adapted to engage said lug to secure the 100 shaft against rotation therein, the lug and pawl being provided with registering perforations for the passage of a seal.

In witness that I claim the foregoing I have hereunto subscribed my name this 18th 105 day of Dec., 1918.

ARGYLE CAMPBELL.
